[57] CLAIM

The ornamental design for an apparatus for dispensing detergent, bleach, and softener in a washing machine, as shown and described.

DESCRIPTION

FIG. 1 is a front elevational view of an apparatus for dispensing detergent, bleach, and softener in a washing machine showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

FIG. 1

FIG. 2

*FIG. 3**FIG. 4**FIG. 5*

FIG. 6
